UNITED STATES PATENT OFFICE.

JOSEPH WINTERBOTHAM, OF JOLIET, ILLINOIS.

STAVE-JOINTING MACHINE.

SPECIFICATION forming part of Letters Patent No. 535,877, dated March 19, 1895.

Application filed March 17, 1894. Serial No. 504,007. (No model.)

To all whom it may concern:

Be it known that I, JOSEPH WINTERBOTHAM, a citizen of the United States of America, residing at Joliet, in the county of Will and State of Illinois, have invented certain new and useful Improvements in Stave-Jointing Machines, of which the following is a specification, reference being had therein to the accompanying drawings, and the letters of reference thereon, forming a part of this specification, in which—

Figure 1 is a perspective view. Fig. 2 is a vertical section of Fig. 1 taken on line 1 looking in the direction of the arrow and Fig. 3 is a perspective view of one of the adjustable stops for controlling the vibration of the stave holder frame.

This invention relates to certain improvements in stave jointing machines, and relates more particularly to that portion of the machine forming a gage for use in adjusting the stave in the machine so as to waste as little of the stave as possible in the operation of jointing it.

Referring to the drawings F is the main frame of the machine, bearing the shaft D journaled in proper boxes in the upper part of said frame. Said shaft has secured on it the fast pulley y and the loose pulley y', to which fast pulley a drive belt is applied, and said shaft has also secured to it a cutter head A carrying a series of cutting bits C, in its side for jointing the stave.

G is a vibrating frame arranged to stand at the side of the cutter head A, near its lower part, and pivotally supported at each of its lower corners in boxes L secured to cross bar F' of the main frame F in such manner that its upper part is free to vibrate to and from said cutter head within the limits of adjustable stops m secured to the main frame F.

E, E are a pair of matching curved clamping levers pivotally connected, one to each upper corner of said vibrating frame G at i, and opposite each other, and having their upper ends curved toward each other and downward so they may be simultaneously clamped down upon the ends of the stave. The opposite lower ends of said clamping levers each pass through a sliding box S' located centrally in frame G in a vertical slot, and having at-

tached thereto the rod V which passes down through an aperture in frame G, and is connected by means of a link V' with arm W secured on rock shaft S. Said rock shaft S has attached to it a foot lever T, which lever when depressed as shown by the broken lines in Fig. 2, will through the medium of said arm W, link V', rod V, and box S', cause the upper ends of arms E to be simultaneously clamped down upon the ends of a stave to hold it firmly in place while being jointed. When the outer end of said foot lever T is relieved from pressure, the weighted inner end N of said foot lever will cause said clamping levers, and the parts connected with them to return to their first position.

O is a post arranged to stand on cross bar F' of frame F, and opposite the center of vibrating frame G at its outer side, and is adjustably secured to said cross bar by means of machine screws C passing through its foot plate, and may have its upper end adjusted to or from the cutter head A by means of loosening some or all of said machine screws, and turning the set screws n that pass through said foot plate. The upper end of said post O has pivotally connected to it an arm P projecting toward said cutter head, and having its outer end turned up at right angles to form a gage for a stave to rest against. The adjustment of the post O to which it attaches being for the purpose of setting said gage to hold a stave at the proper place while being jointed to save as much of the stave as possible. Said gage arm P is connected with arm W of rock shaft S by means of the rod R pivotally connected to said gage, near its pivoted inner end, and which rod passes through an eye Z' on the side of arm W loosely. Coil springs Z are sleeved on said rod, one on either side of said eye, and in contact therewith, and held in such contact by means of nuts turned on said rod, so as to yieldingly hold said gage P in proper position for gaging a stave in the machine. Pressure on foot lever T will through the medium of rod R cause gage P to swing down as shown in broken lines in Fig. 2, out of the way of the vibrating frame G and stave. At the same time clamping levers E are clamped on the stave, to hold it while being jointed as

before stated, and when said foot lever is released from pressure its weighted end N will cause said gage to return to its first position.

H, H, are a pair of arms secured to a rock 5 shaft J having its ends journaled in boxes L' on the inner side of vibrating frame G at about its center, which arms are curved at their upper ends toward the cutter head A to engage the rear edge of a stave and carry 10 it forward to the gage P, and hold it in contact with the stave by means of the weighted arm K secured to said rock shaft J, thus forming a pair of gravity clamps against which the stave is placed and carried forward by them 15 to the gage P, and also for the purpose of giving proper alignment to the stave while being jointed.

B is a case for inclosing the back and periphery of the cutter head, and forming a receptacle for the shavings which discharge 20 from a spout in the periphery of said case, and shown in Fig. 1.

In operation a stave is placed on the upper 25 face of the vibrating frame G so its center will rest on the bilge block r, and its ends, on a similar rest at each end of the frame under the clamp levers E, and with its rear edge in contact with the two clamps H which give it the proper alignment and carry it forward 30 against the gage P, when by means of pressing down on the outer end of foot lever T, the

two clamp levers are brought down on the ends of the stave to hold it firmly in place, and simultaneously the gage P is caused to swing down from the stave and out of the way of 35 the frame G and stave, while the frame G is oscillated forward within the limits of the stop m to bring the edge of the stave up to the cutter head A to be jointed. Such oscillation of frame G is caused by reason of the 40 foot lever being connected with it by means of the link V', and rod V as shown in Fig. 2. The stops m and the gage P are adjusted so as to prevent any more of the stave being planed off and wasted than is absolutely necessary. 45

Having thus described my invention, what I claim as new, and desire to secure by Letters Patent, is as follows, to wit:

In a stave jointing machine the combination 50 of the vibrating frame G, gravity clamps H, K, clamping levers E, E, sliding box S' carrying said lever, rod V, link V', foot lever T, N, lever W, shaft S, standard O, gage P, rod R having the coil springs and nuts Z, Z, 55 and the adjustable stops m, all arranged to operate substantially as and for the purpose set forth.

JOSEPH WINTERBOTHAM.
